US00D992902S

(12) **United States Design Patent** (10) Patent No.: **US D992,902 S**
(45) Date of Patent: **** Jul. 25, 2023**

(54) **EARPHONE CASE**

(71) Applicant: **Roland Corporation**, Shizuoka (JP)

(72) Inventors: **Teruyoshi Kobayashi**, Shizuoka (JP);
Andrea Grecucci, Milan (IT)

(73) Assignee: **Roland Corporation**, Shizuoka (JP)

(**) Term: **15 Years**

(21) Appl. No.: **29/795,705**

(22) Filed: **Jun. 21, 2021**

(30) **Foreign Application Priority Data**

Dec. 23, 2020 (JP) ..... 2020-027779 D

CLAIM

The ornamental design for an earphone case, as shown and described.

DESCRIPTION

FIG. 1 is a perspective view of an earphone case showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings depict portions of the earphone case that form no part of the claimed design.
